SECTIONAL DIRECTORY

Elwin M. Sommers, Chicago, Ill., assignor to The
Tablet & Ticket Company, Chicago, Ill., a cor-
poration of Illinois

Application January 15, 1934, Serial No. 706,597

4 Claims. (Cl. 40—63)

The present invention relates to sectional di-
rectories such as those customarily employed for
directory purposes in large buildings, and has partic-
ular reference to improvements in the con-
struction of such devices.

A principal object of the invention is the pro-
vision of a sectional directory which is neat in
appearance, sturdy, and economical in construc-
tion.

10 An additional object is to provide a sectional
directory from which the individual sections may
be removed with ease and replaced in properly
adjusted position.

A further object is to provide a sectional di-
rectory which will retain the individual sections
in adjustable and secure relation with respect to
each other and to the directory frame structure.

These and other objects will be apparent upon
consideration of the following description and by
20 reference to the accompanying drawing, in which

Fig. 1 is a front elevation view of a building
directory or changeable sign constructed in ac-
cordance with my invention;

Fig. 2 is a cross-sectional view taken along line
25 2—2 of Fig. 1;

Fig. 3 is a view similar to Fig. 2 and shows the
operation of mounting an individual directory
section in the main frame;

Fig. 4 is a rear view of the sectional directory
30 shown in Fig. 1;

Fig. 5 is a fragmentary sectional view taken
along line 5—5 of Fig. 4 and shows in detail the
construction of one unit of the lateral adjusting
mechanism of the directory; and

35 Fig. 6 is a fragmentary sectional view taken
along line 6—6 of Fig. 4 and shows in detail the
construction of the main frame and header
channel.

Sectional building directories consist generally
40 in a main frame structure having means for sup-
porting one or more individual sectional frame
structures. These individual or auxiliary units
have a backing member and letters attachable
thereto for display purposes. For instance, in
45 large buildings the names of tenants are listed
alphabetically, with the proper room number ap-
pearing opposite each name.

The structure of the directories known hereto-
fore is exemplified in Patents Nos. 454,424 and
50 560,878, issued to Henry Willson, and No. 1,181,-
641, issued to Burnside. A common structure for
mounting the auxiliary or individual frame struc-
tures within the main directory frame has con-
sisted in a lower rack and an upper rack having
55 a plurality of backing bars therebetween and

passing transversely of the directory frame to
engage the backs of the auxiliary frame members.
Particularly in the case of relatively wide direc-
tories, this type of structure has been found un-
satisfactory for several reasons, including the in-
secure mounting of the auxiliary frame members
and their tendency to become loose within the
main directory frame.

In accordance with the present invention, a
highly satisfactory mounting structure is pro-
vided by a particular arrangement of an upper
header channel and a lower rest channel spaced
apart by suitable vertical side members extending
inwardly beyond the ends of the channels, the
vertical side members having adjustable means
extending inwardly from the ends of the channels
and situated behind the inner edge of the side
members for adjusting the lateral position of the
individual or auxiliary frame structures.

As shown in the drawing, the directory is con-
structed of a main frame 10 which ordinarily is
of heavy brass or bronze capable of withstanding
the severe use to which directories of this type
are subjected. The upper portion of the directory
is provided with a rectangular laterally-extend-
ing opening which is covered by a plate 11 carry-
ing suitable information such as the word "Di-
rectory", as shown in Fig. 1. This plate is held
in place over the rectangular opening by means
of suitable clamps 12 and a set screw 13.

Directly beneath the plate 11 is fixed an upper
header channel 14 formed by a vertical front
plate 15, a horizontal upper plate 16 and a down-
wardly and inwardly extending rear plate 17.

At the bottom of the frame structure 10 is pro-
vided a rest channel 18 formed by a vertical front
plate 19, a horizontal lower plate 20 and a vertical
rear plate 21 extending laterally of the frame.

The header channel 14 and the rest channel
18 are joined by vertical side members 22 which
space the channels apart a distance sufficient to
accommodate therebetween the individual or aux-
iliary frame structures 23. Side members 22 are
provided with front plates 24 which extend in-
wardly beyond the ends of header channel 14 100
and rest channel 18. In the preferred modifica-
tion of the invention the plate 24 will take the
place of portions of the front walls 15 and 19, as
shown in Fig. 6 of the drawing.

The directory shown in the drawing is of the
type accommodating three auxiliary frame sec-
tions 23, each of which has an outer bronze frame
25 provided with a key opening 26 in its lower edge
designed to permit of easy insertion and removal
of the auxiliary frame structures from the main 110

frame, as will be described. Within the frame 25 is mounted the usual backing member upon which is mounted suitable words, names, numbers and the like, and a front plate glass protective member. Where three auxiliary units 23 are employed in a building directory, the names of tenants beginning with the letters A to I, for example, may be mounted in the first unit, names beginning with letters J to Q in the second unit, 10 and names beginning with letters R to Z in the third unit.

After the names are properly listed, the individual units are mounted in the main frame.

In accordance with my invention, the width of 15 upper plate 16 is sufficient to space front wall 15 and rear wall 17 apart a distance greater than the width of frame structures 25 of the individual directory units, and the rear wall 17 is extended inwardly and downwardly so that its distance 20 from the front wall 15 will be substantially equal to or only slightly greater than the width of frame structures 25 at a point adjacent the lower edge of the front wall 15, as will be seen in Figs. 2 and 3. Also, lower plate 20 of the rest channel 25 18 is of sufficient width that the latter will be of substantially the same width as the frame structure 25 of the auxiliary directory units. Front wall 19 of the rest channel 18 is of considerably less height than front wall 15 of the 30 header channel.

The individual frame units are mounted in the manner shown in Figs. 2 and 3. That is, the upper edge of a unit 23 is pressed upwardly into the header channel 14 from the front of the 35 main frame, and at an angle thereto, as shown in Fig. 3. When the lower edge of the unit 23 has cleared the front wall 19 of the rest channel 18, it is then pressed inwardly until it contacts the rear wall 21 of the rest channel and allowed 40 to drop by gravity into engagement with the horizontal wall 20, thereby securely locking the lower edge of the unit against accidental removal or displacement.

As the unit 23 is lowered into the position 45 shown in Fig. 2, the upper edge of the unit is lowered to a point slightly above the lower edge of the front wall 15 of the header channel.

After being mounted in the header and rest channels in the manner described, the outer auxiliary units are moved outwardly along the channels to a position adjacent the ends thereof and to such an extent that the vertical edges of the units pass back of front plates 24 of the upright frame members 22, as shown in Fig. 5. The 55 central unit is then mounted in the frame to complete the assembly.

To limit the outward or transverse movement of the units when mounted in the manner described, I have provided adjustable means situated on the rear side of plates 24 and extending inwardly of the ends of the header and rest channels for engaging the vertical sides of individual directory units 23 when the latter are in predetermined position with respect to the channels and front plates 24. As shown in the drawing and particularly in Figs. 4 and 5, a plurality of block members 27 are secured to the rear side of front plates 24 in any suitable manner. There are two oppositely positioned block members 27 60 adjacent the header channel and a like number of similarly disposed block members adjacent the rest channel.

Each block is internally threaded to receive an inwardly extending eccentric screw member 28.

75 To properly position the auxiliary frame units

within the header and rest channels, the several eccentric screws 28 are adjusted to such position as to engage the outer edges of the units when the latter have moved outwardly behind the front plate members 24 a proper distance. This adjustment is such that the several auxiliary units fit together snugly when completely assembled. The outer edges of the auxiliary frame units extend outwardly beyond the inner edges of plates 24 and the heads of screws 28 are adjustable intermediate the ends of the header and rest channels and the inner edges of plates 24. The eccentric structure of the screw members insures that their adjusted position will be maintained. The eccentricity of the screw members may be obtained in one way by damaging the threads of the screw on one side. By making the front slightly oversize, substantially the same result will be obtained. Any other well known means of providing eccentricity of the screw may be employed.

Various changes in the above described structure may be made without departing from my invention, and all such modifications are intended to be included in the appended claims.

I claim:

1. A sectional directory, comprising a main frame structure having an upper header channel, a lower rest channel, and vertical side members extending between said channels and spacing the same apart a distance sufficient to accommodate sectional frame structures therebetween, the width of said rest channel being substantially that of a section frame structure, the depth and width of said header channel being 105 greater than the depth and width of the rest channel, and the rear wall of said upper channel extending downwardly and inwardly to provide an opening adjacent the lower edge of the front wall of said header channel of substantially 110 the same width as the width of the rest channel; and adjustable means situated behind the vertical side members for determining the position of sectional frame members within said channels, said means having sectional frame contacting members extending inwardly of the ends of said channels.

2. A sectional directory comprising a main frame structure having a lower rest channel, an upper header channel of greater depth and width 125 than the depth and width of said lower channel, whereby to allow insertion of an auxiliary directory frame unit in said main frame by angular insertion in said header channel and lowering into said rest channel, vertical side members 130 extending between said channels and spacing the same apart a distance sufficient to accommodate auxiliary directory frame units therebetween, said vertical side members extending inwardly of the outer ends of said channels on the front side 135 thereof, and at least three auxiliary directory frame units positioned in said channels, the outermost of said units being positioned behind said vertical side members, and the intermediate unit fitting snugly against said outermost units to 140 maintain the latter in position behind said vertical side members, and means for determining the outermost position of said outermost units in said channels.

3. A sectional directory of the structure specified in claim 2, in which the intermediate auxiliary frame unit is provided with means for removal of said unit from the main frame.

4. A sectional directory, comprising a main frame structure having a lower rest channel, an 150

upper header channel of greater depth and width than the depth and width of said rest channel, whereby to allow insertion of an auxiliary directory frame unit in said header channel and lowering into said rest channel, vertical side members extending between said channels and spacing the same apart a distance sufficient to accommodate auxiliary directory frame units therebetween, said vertical side members extending in-

wardly of the outer ends of said channel on the front side thereof, and adjustable means situated behind the vertical side members for determining the position of sectional frame members within said channels, said means having sectional frame contacting members extending inwardly of the ends of said channels and terminating behind said vertical side members.
